W. J. SMITH.
WIRE FENCE REPAIRER.
APPLICATION FILED AUG. 29, 1914.

1,161,740.

Patented Nov. 23, 1915.

UNITED STATES PATENT OFFICE.

WILLIAM J. SMITH, OF EOLIA, MISSOURI.

WIRE-FENCE REPAIRER.

1,161,740.

Specification of Letters Patent. Patented Nov. 23, 1915.

Application filed August 29, 1914. Serial No. 859,229.

To all whom it may concern:

Be it known that I, WILLIAM J. SMITH, a citizen of the United States, residing at Eolia, in the county of Pike and State of Missouri, have invented a new and useful 5 Wire-Fence Repairer; and I do hereby declare the following to be a full, clear, and exact description of the invention, such as will enable others skilled in the art to which it appertains to make and use the same.

This invention relates to an improved wire stretcher having means whereby the loose or slack wire after the wire has been stretched may be twisted, or in other words 10 shrunken.

An object of the invention is to provide a device of this nature involving simple, efficient, and practical features of construction.

In practical fields the details of construction may necessitate alterations, falling 15 within the scope of what is claimed.

The invention comprises further features and combination of parts, as hereinafter set forth, shown in the drawings and claimed.

In the drawings: Figure 1 is a view in perspective, showing the head of the device fulcruming against a post and a wire caught between the clenching jaws so as to be stretched. Fig. 2 is a view showing the wire adjacent one post being twisted, the remaining portion of the wire having been stretched, in this manner the slack wires, after a wire has been stretched beyond both sides of the post, are shrunk. Fig. 3 is a 20 detail view showing the head of the device being utilized as a staple puller. Fig. 4 is a view showing the pieces of wire being cut. Fig. 5 is an edge view of the tool, more clearly showing how the extension 12 may be adjusted, so that the teeth 9 and 14 may be separated farther apart. Fig. 6 is an edge view of a portion of the tool, showing the extension 12 bolted in place, so as not to be 25 adjusted. Fig. 7 is a perspective view, showing how the slack or loose wire is shrunk and twisted. Fig. 8 is a view in elevation, showing the manner of shrinking or twisting the wire, and how the staples are arranged to engage the loops of the twisted wire.

Referring more especially to the drawings, 1 designates a handle member, and 2 a jaw member pivoted at 3 to the handle member 1, said jaw member having a handle portion 4. The jaw member and the handle member are provided with notches 5 and 6, the walls of which are inclined as shown,

and the notch 5 is provided with a cutting edge 7 to coöperate with a cutting edge 8 of the notch 6, for severing a piece of wire when inserted in said notches. The jaw member is provided with a curved end edge having clenching teeth 9. The handle member at one end is provided with a dove-tailed recess 10, to receive a dove-tailed tongue 11 of an extension 12, so as to hold 60 the extension upon one face of the handle member, thereby affording a shoulder 13 having teeth 14. A thumb screw 15 passes through the extension and into the handle member adjacent the dove-tailed tongue and 65 groove or recess, for holding the extension 12 in adjusted positions, which may be adjusted toward and from the tooth curved edge of the jaw member, so that wires of different thicknesses may be clenched between 70 75 said teeth.

As shown in Fig. 6 the extension 12 is bolted by means of the bolts 12^a to the handle member 1, so that the extension 12 need not be adjusted. The extension 12 is 80 provided with a head 17 having a broad end, which fulcrums upon a post when stretching a wire, which is placed between said clenching teeth, which are alined directly with the center of said head, and 85 owing to the broad end of the head, the twisting of the tool when stretching a wire is reduced to a minimum. The other end of the head terminates in a pointed curved portion 18 to be inserted in a staple for extracting the same. The handle member 1 is provided with an additional extension 19 extending at an angle to the body of the handle member. Upon both sides of the handle member adjacent just where the extension 90 95 19 (which is disposed at an obtuse angle to the handle) merges into the body of the handle member are plates 20 secured in place by the rivets or other suitable means 21. These plates 20 are provided with duplicate 100 U-shaped portions 22 projecting beyond the edge of the handle member, the ears or flanges 23 of said U-shaped portions extending in opposite directions.

As shown in the drawings there is a plurality of posts 25, 26 and 28 illustrated. The wire as indicated at 40 and 41 beyond the posts 25 and 28 has been stretched, and the wire between said posts 25 and 28 is supposed to be loose or slack. This portion 42 110 of the wire is the part which is to be twisted or shrunk, and the twisted portion

fastened to the post 26. To accomplish this the tool is placed, so that the wire 42 passes between the adjacent faces of the U-shaped portions of said plates 20, as shown clearly in Figs. 2, 7 and 8, then the tool is twisted or turned in the direction indicated by the arrow *a* in Fig. 2, the wire or portion 42 twisting or coiling about the U-shaped portions 22, as shown clearly in Figs. 7 and 8. After that portion of the wire 42 has been twisted or coiled as shown in Figs. 7 and 8 a pair of staples 43 are inserted between the flanges or ears 23 of the U-shaped portions 22, and driven into the post 26, thereby fastening the wire to the post, and after the staples are completely driven home, said U-shaped portions are then removed from the loops in the wire.

The invention having been set forth, what is claimed as new and useful is:—

An operating tool for coiling loose or slack wire, comprising a handle member having an extension extending at an obtuse an-

gle to the handle member, a pair of plates secured directly opposite one another upon opposite faces of the handle member at the junction where said extension blends into the handle member, said plates being extended beyond one edge of the handle member and terminating in U-shaped portions comprising flanges extending in opposite directions and parallel to each other, whereby upon imparting a turning movement to the handle member the slack wire coils about said flanges of the U-shaped portions, said U-shaped portions being designed to receive the staples which straddle the wire of the coil.

In testimony whereof I have signed my name to this specification in the presence of two subscribing witnesses.

WILLIAM J. SMITH.
